MOBILE CONCRETING PUMP

Marvin D. Bennett, Wilmington, Calif., assignor to Royal
Industries, Inc., Gardena, Calif., a corporation of
California

Filed Mar. 1, 1965, Ser. No. 84,013

Term of patent 14 years

(Cl. D14—3)

Des. 203,746

PAGE 2

FIG. 1 is a left hand perspective view of a mobile concreting pump showing my new design.

FIG. 2 is a right hand perspective view of a mobile concreting pump.

FIG. 3 is a top perspective view of a mobile concreting pump.

The dominant features of my design reside in the portions shown in full lines.

I claim:

The ornamental design for a mobile concreting pump, as shown and described.
